Primary Examiner — Barbara Fox*Assistant Examiner* — Dana K Weiland*(74) Attorney, Agent, or Firm* — NSIP Law(57) **CLAIM**

The ornamental design for a tablet computer, as shown and described.

DESCRIPTION

FIG. 1 is a front perspective view of a tablet computer, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a front perspective view of a tablet computer of FIG. 1, in which a keyboard in broken lines is provided to illustrate an example environment;

FIG. 9 is a rear perspective view of a tablet computer of FIG. 1, in which a keyboard in broken lines is provided to illustrate an example environment and the tablet computer is in a closed position with respect to the unclaimed keyboard; and, FIG. 10 is a partially enlarged view taken along line 10 in FIG. 1.

Speaker holes shown in a left portion and a right portion of the tablet computer in FIGS. 1, 2 and 8 are unclaimed features as illustrated by FIG. 10, showing the partially enlarged features in broken lines.

The broken lines shown in the drawings represent portions of the tablet computer that form no part of the claimed design. The shade lines in the figures show contour and not surface ornamentation.
